(57) **CLAIM**

The ornamental design for a hand and forearm stretching device, as shown and described.

DESCRIPTION

FIG. 1 is a perspective view of an hand and forearm stretching device;

FIG. 2 is a front view thereof;

FIG. 3 is a back view thereof;

FIG. 4 is a first side view thereof;

FIG. 5 is a second side view thereof;

FIG. 6 is a top view thereof; and,

FIG. 7 is a bottom view thereof.

The broken line wavy break lines in FIGS. 1-7 indicate a symbolic break in length and form no part of the claimed design. The appearance of any portion of the article between the break lines forms no part of the claimed design. The dot-dash broken lines in FIGS. 1, 3-5 and 7 indicate portions of the device that form no part of the claimed design.

1 Claim, 4 Drawing Sheets
